(57) CLAIM

I claim the ornamental design for a housing for a fluid treatment device, as shown and described.

DESCRIPTION

FIG. 1 An upper front right perspective view of a housing for a fluid treatment device showing my new design with inlet/outlet connections, shown in dashed lines, not forming part of my design;

FIG. 2 A upper front right perspective view, with the unclaimed portions removed;

FIG. 3 A front elevation view, with unclaimed connections shown in dashed lines;

FIG. 4 A right side elevation view thereof;

FIG. 5 A rear elevation view thereof;

FIG. 6 A left side elevation view, with unclaimed connections shown in dashed lines; and,

FIG. 7 A top plan view, with unclaimed connections shown in dashed lines.

The bottom plan view is flat, unornamented and contains no part of the invention; therefore, it is not illustrated.
